UNITED STATES PATENT OFFICE.

WILLIAM SEAMAN SCOTT, OF MAPLEWOOD, NEW JERSEY.

METHOD OF AND APPARATUS FOR OBTAINING POWER FROM THE SURF.

1,418,680.

Specification of Letters Patent. Patented June 6, 1922.

Application filed July 7, 1917, Serial No. 179,108. Renewed November 4, 1921. Serial No. 512,938.

To all whom it may concern:

Be it known that I, WILLIAM SEAMAN SCOTT, a citizen of the United States, and a resident of Maplewood, in the county of 5 Essex, State of New Jersey, have invented an Improvement in Methods of and Apparatus for Obtaining Power from the Surf, of which the following is a specification.

My invention relates to a method and 10 apparatus for utilizing the energy of ocean waves as they break upon a shore, and contemplates the storage of such energy in the form of compressed air, or water power, and its use in either or both of such forms, in 15 suitable power translating devices.

In the practice of my invention, I make use of the impact force of a breaking wave, to produce movement of a mass of water into a container against the pressure of a 20 head of water, and also to propel into said container and compress therein, air carried in the water, or trapped by the movement of the wave in the manner hereinafter described.

My invention also contemplates certain 25 modifications, whereby the energy may be partly or entirely stored in the form of compressed air at moderate pressures, as up to fifty or sixty pounds per square inch, and 30 also the provision of means whereby air at different pressures may be simultaneously obtained from different portions of my apparatus.

In the drawings forming a part of this 35 specification, I have illustrated more or less diagrammatically, and without reference to absolute or relative dimensions, examples of the various forms which my apparatus or parts thereof may take. It should be 40 understood, however, that the forms illustrated are not the only ones my apparatus is capable of taking, and that they are shown herein merely by way of illustration, and that many modifications and changes 45 may be made without departing from the spirit of my invention.

In Fig. 1, I have shown a plan view of my apparatus;

In Fig. 2, a side view thereof partly in 50 section, the section being taken on the lines 2-2 of Fig. 1;

In Fig. 3, a sectional view of a modification of my invention;

In Figs. 4, 5 and 6, detail views of one 55 form of a portion of my apparatus;

In Figs. 7 and 8, detail views of another form of a portion of my apparatus;

In Fig. 9, a detail view of a portion of the apparatus illustrated in Figs. 4 to 8 inclusive; and in

Figs. 10 and 11, detail views showing a valve mechanism which may be used with my invention.

Referring to Figs. 1 and 2, my apparatus comprises a closed, separating chamber 1, 65 preferably, as shown, of elongated form, so as to permit substantially complete separation of the air from the water in which it is entrapped before the water reaches the standpipe and overflow subsequently to be 70 described. The chamber 1 is preferably, as shown, above the ground and is also preferably not below but even slightly above, the level of the waves and is located in 75 proximity to a beach, and preferably outside of the destructive action of the waves. The separating chamber 1 is air and water tight and serves as a space in which the mixed air and water are separated from each other.

Connected to the chamber 1 and extending 80 towards the sea, are a plurality of pipes 2, which may be supported by piles 3 sunk in the beach by any suitable or convenient method. Pipes 2 carry at their outer ends, 85 wave-receiving means 4, which may be in the form of funnels, and which may take any suitable form, examples of which are illustrated in Figs. 4 to 8. The wave-receiving means 4 are preferably located to 90 follow the general line of the approaching waves on the beach, and to receive the impact of the breaking wave under the various conditions of tide. To accomplish these results, they may be superimposed or arranged 95 in echelon, or in any other suitable manner.

Between the wave-receiving means 4 and the separating chamber 1 is located a gate valve 5, or any other hand-operated cut-off and an automatic valve, such as the check 100 valve 6, permitting the flow of the water towards the separating chamber 1, but preventing the flow away from it. A second gate, or hand-operated valve, 7, is preferably located close to the container. The gate 105 valves 5 permit, when closed, the examination and repair of the automatic valves 6.

Valves 5, 6 and 7 should be of a suitable size to permit the full, free flow of water carried by the pipes 2 to pass through them 110 with the least possible retardation or ob-

- struction. In order to reduce or check the high velocity of the water in the pipes, the latter are preferably provided with portions of gradually increasing cross-section, as indicated at 8, preferably adjacent those points of the pipes 2 where the latter approach the separating chamber 1. Located opposite the inlet pipes 2 in the separating chamber 1 are baffle plates 9 or other suitable means for breaking the impact of the water when it reaches the separating chamber 1. The second series of gate valves 7 is preferably placed between the automatic valves 6 and the enlarged portions 8 of the pipes 2.
- 15 The container may also be supplied with suitable openings, indicated at 10, to permit cleaning out sand or rubbish which may penetrate within it.
- Connected to the container 1, and preferably located at a point a considerable distance from pipes 2, is a stand pipe 11, communicating with the container 1 by means of an orifice 12, which is lower than the height of the container 1. In said stand pipe there is consequently maintained a column of water which, after the apparatus has been operating for some time, is of a substantially constant, predetermined height above the level of the incoming water. This column of water of substantially constant height exerts a substantially constant pressure upon the air within the separating chamber, so that the intermittent impulses of the waves entering the funnels are not directly communicated to the air within the separating chamber. Stand pipe 11 communicates at its top with downflow pipe 13, and is provided with a spillway 14 for any excess of water. The lower end of the downflow pipe 13 is connected, in any suitable manner, to suitable translating devices, such as turbines or Pelton wheels, indicated diagrammatically at 15, said translating devices being supplied with an outflow pipe 16. I preferably arrange the spillway 14 to empty into a catch-basin 17, having an overflow 18. The water falling from the spillway thus falls upon the body of water in the catch-basin 17, and prevents destructive action due to the height from which it falls. The water from the waste weir and that from the translating devices is carried back to the ocean by any suitably located channel, said channel being preferably so located that the flow will not disturb the other operative portions of the device.
- Container 1 is also provided with a blow-off pipe or governor 19 and outlets 20, for compressed air service pipe.
- 60 The operation of the device described thus far is substantially as follows: The surf, breaking into the wave-receiving devices 4, forces at each wave, a certain amount of water mixed with air into the pipes 2, past the automatic valve 6 into the container 1.

The water is there deflected by the baffle plates 9, and the air held in the water is given up, rising to the top of the container. The level of the water in the container 1 is thus raised. At first the air escapes freely up the stand pipe until the level of the water has reached the upper edge of the orifice 12, into the stand pipe 11. At this point the air is sealed against escape into stand pipe 11. The blow-off pipe 19, which is preferably provided with a bell mouth, as indicated in Fig. 2, is then sealed by the rising water, and a certain quantity of air is trapped between the level of the water and the top of the container 1. Further increments of 80 water entering through the funnels 4 into pipes 2 serve to raise the level of the water in the stand pipe 11, thus compressing the air trapped in the upper part of container 1, and the decreasing of the volume of this 85 trapped air is compensated for by further air introduced with the further increments of water. The operation of the device thus continues, the level of the water in stand pipe 11 being constantly raised, and the 90 air being therefore compressed to a higher pressure, until the level of the water reaches the top of the stand pipe 11 and overflows into the downflow pipe 13. After this level has been reached, the air is maintained at a 95 constant pressure (as long as the stand pipe 11 is full of water,) the height of the column of water in stand pipe 11 regulating the air pressure within the separating chamber. If more air accumulates, there is 100 drawn off for service any excess of air, any further excess of air being discharged through the blow-off pipe 19, or through the stand pipe 11. There is thus available a supply of compressed air which may be 105 drawn off as needed, through the service pipe 20 and supplied to suitable translating devices at a substantially constant pressure.

The overflow of water into the downflow pipe 13 may be utilized for the purpose 110 of driving suitable translating devices, and if the water requirements of such devices are properly designed, they will be kept constantly operating under a head of water equivalent to the height of the downflow 115 pipe 13. The compressed air and the water from the downflow shaft may be used for any other desired purpose, as for example, for directly lifting water from the drainage canal of tidal or other marshes.

120 It will be understood that the arrangement of stand pipe and downflow pipe may be duplicated, as illustrated in Fig. 1, and that a number of such pairs of pipes may be provided with a common spillway, as indicated in said drawing.

In the modification illustrated in Figs. 1 and 2, it is evident that the pressure of the air in the separating chamber 1 is regulated by the height of stand pipe 11, each twenty- 130

seven and one half inches in height of the water column corresponding to one pound pressure per square inch on the air in separating chamber 17. It may be desirable, 5 at certain times, to secure compressed air at higher pressures. For this purpose, I prefer to use the modification illustrated in Fig. 3, which gives good results up to one hundred and thirty or even one hundred and 10 fifty pounds of pressure per square inch.

In this modification, I make use of the separating chamber 1, provided with the blow-off pipe 19, stand pipe 11, compressed air service pipe 20, and the funnel, pipe and 15 valve apparatus for introducing air and water therein. I, however, provide, in addition to said separating chamber, an underground separating chamber 21, which may be located at any convenient depth, depending 20 upon the pressure desired. Instead of using the water in the downflow pipe 13 to operate translating devices 15, as in the modification shown in Figs. 1 and 2, I make use of said water to gather and compress an 25 additional supply of air in the underground chamber 21 in the following manner:

Chamber 21 is provided with a blow-off pipe 22, a service compressed air outlet pipe 23, and an outflow shaft 24, which communicates with chamber 21 by means of an aperture 25 of less height than the height of chamber 21. The downflow shaft 13 is provided at its top with suitable air inlets 26, and communicates at its bottom with chamber 21. I preferably enlarge the lower end of downflow shaft 13, as indicated at 27, and provide a suitable baffle plate 28 to disperse the stream of water flowing through the downflow shaft 13. The operation of 40 this apparatus is essentially as follows:

Air is compressed in chamber 1, as in the modification of Figs. 1 and 2, and the level of water in stand pipe 11 rises until it overflows into downflow shaft 13. When the 45 water overflows in this manner, it sucks into downflow shaft 13 a certain quantity of air through the air inlets 26, which air is carried down to the lower chamber 21 and there given off, rising to the top of chamber 21. As more water and air is carried down 50 downflow shaft 13, the level of the water in outflow shaft 24 rises, thus compressing the air, and more air is supplied to the upper part of chamber 21. I am thus enabled to supply compressed air from air outlet 20 of chamber 1, at a pressure which is a function of the height of stand pipe 11, and I am able to supply air through outlet pipe 23 at a pressure which is a function of the 55 height of outflow shaft 24.

If desired, and if the supply of water is sufficient, a portion of the water flowing through downflow shaft 13 may be used to operate translating devices, such as illustrated in Figs. 1 and 2. Among the devices 60

which may be operated by the apparatus of my invention, for example, may be a stage compression device for very high-gage air compression, utilizing the air from separating chamber 1 for the first stage of the air 70 compression.

It will thus be seen that in the first modification described, the container 1 is an air and water tight chamber so constructed that the upper portion thereof is a compressed 75 air chamber, and the lower portion a large passage for the water, so that the water will move slowly from the entrance pipes to the stand pipe and give up its contained air. The gradual enlargement of the entrance 80 pipes and the baffle-plates assist in reducing the speed of movement of the water, and thus permit it to give up more of its air than it otherwise would. The top of the connection between the chamber and the 85 stand pipe constitutes a water seal for the compressed air, and the height of the water in the stand pipe regulates the air compression, and being always full, maintains a substantially constant pressure upon the air, 90 thereby stabilizing such compressed air for power purposes.

In the second modification, the underground chamber is so constructed that the upper portion is a compressed air chamber 95 and the lower portion a large passage for the water, which will give up its contained air as it slowly passes from the downflow shaft to the outflow shaft. The top of the waterway in the chamber at each shaft forms 100 a water seal for the compressed air. The difference in level between the tops of the downflow and outflow shafts gives the power head, and the difference in level between the water in the chamber and the top of the 105 outflow shaft gives the air compression head. It will thus be noted that in both the surface and underground chambers the air is compressed isothermally and not adiabatically, and for this reason a maximum efficiency for power purposes is obtained.

In Figs. 4 to 8, I have illustrated some modifications of the wave-receiving devices or funnels 4, the modification illustrated in Figs. 4, 5 and 6 being an arrangement of 115 three superimposed funnels, having straight converging sides, although said funnels may be formed with parabolic, or otherwise curved sides, as indicated in Fig. 1. This arrangement of funnels permits operation 120 of the same at all stages of tide. The effect of such restriction of the funnels is to concentrate the concussive force of the waves upon their small inner ends. In Fig. 4, three of such funnels are shown having the pipes 125 connected thereto slightly offset, so as to permit access to the gate valves 5 and automatic valves 6, the latter being illustrated in Fig. 4 as being a vertically hinged flap valve. When said funnels are superim- 130

posed, they may be conveniently supported by means of spacing members 29, which tend to make a rigid structure, adapted to arrest the impact of the waves. The mouths 5 of funnels 4 are preferably covered with a screen or grill 30, to prevent the entrance of debris, seaweed, etc., and to break up the waves so that they will gather free air, and the bottom of the funnels are forwardly inclined to permit quick reflux of the waves 10 and to permit the funnels to fill with air before the next wave strikes into the mouth thereof, the mouths of the funnels are preferably inclined, as indicated in Fig. 6, so 15 that the debris collecting upon screen 30 may fall off by gravity.

I preferably provide the lower edge of the lowermost funnel with a lip 31, which may be constructed, as shown in Fig. 9, from 20 sheet steel. This lip permits the easy ingress of the wave, forces a larger body of water against the mouth of the funnel, and directs the scour of the receding wave away from the piling or other support of the funnels. 25 If desired, the lower edges of the funnels of the upper tiers may be provided with similar lips, but I find that the prolongation of the lower wall of the upper funnels, as indicated at 32, is sufficient.

In Figs. 7 and 8, I have shown an arrangement of funnels, in which two funnels are superimposed, the bottom of each shelving towards the top and being provided with slightly offset pipes to permit access to the 35 gate valves 5 and check valves 6. In this case, the check valves are illustrated as being horizontally hinged flap valves, and the funnels are illustrated as being provided with a lip 31 and a grating 30, as in the 40 other modifications.

In Figs. 10 and 11, I have illustrated a modified form of valve, which comprises a plurality of poppet valves seated in a disk 33, and guided by a disk 34. This design 45 of valve permits of a very wide opening, and by reason of the relatively small size of the constituent valves, is subject to less impact force upon the seating of the valves than in the flap valves illustrated in Figs. 50 4 and 7. It should, however, be understood that my invention is not confined to any particular form of valve, and that these may be varied to best suit the requirements of practice, as may be the other portions of my 55 apparatus described above.

I claim:

1. In a device of the kind described, a 60 chamber, a plurality of wave-receiving means connected thereto, a stand pipe communicating with said chamber, an outflow pipe communicating with the stand pipe adjacent its upper end, and a second chamber located at a lower level than the first chamber and connected to the outflow pipe.

2. In a device of the kind described, a 65 chamber, adapted to contain a body of air and a body of water, a plurality of wave-receiving means adapted to deliver air and water thereto, a stand pipe communicating with the portion of the chamber containing 70 water, an outflow pipe communicating with the stand pipe adjacent its upper end, a second chamber located at a lower level than the first chamber, and adapted to contain a body of air and a body of water, the portion 75 of said chamber adapted to contain a body of water being connected to the outflow pipe.

3. In a device of the kind described, a 80 chamber, adapted to contain a body of air in its upper portion and a body of water in its lower portion, a stand pipe connected to the lower portion of the chamber, a downflow pipe communicating with the stand pipe adjacent its upper extremity, a second chamber located at a lower level than the first 85 chamber, and adapted to contain a body of air in its upper portion, the lower portion thereof being connected to the downflow pipe, and an outflow shaft connected to the 90 lower portion only of said lower chamber.

4. In a device of the kind described, a 95 chamber, adapted to contain a body of air in its upper portion and a body of water in its lower portion, a plurality of wave-receiving means connected to the lower portion of said chamber, means for permitting the flow of water in one direction only between said wave-receiving means and said chamber, a stand pipe connected to the lower portion of said chamber, a downflow pipe communicating with the stand pipe adjacent its upper extremity, a second chamber located at a lower level than the first chamber, and adapted to contain a body of water in its lower portion and a body of air in its upper portion, the lower portion of said chamber being connected to the said downflow pipe, and an outflow shaft connected to the 100 lower portion only of said lower chamber.

5. In a device of the kind described, wave-receiving means, comprising a funnel, provided with a lip attached to the lower edge of the funnel and projecting forwardly and outwardly therefrom.

6. In a device for obtaining power from 115 waves, the combination with an air and water separating chamber positioned substantially at the level of the incoming waves, of one or more wave-receiving means discharging into said chamber for delivering the incoming waves to said chamber substantially at the level of the same, a stand pipe connected to said chamber adjacent the bottom thereof and extending above said chamber and also above the level 120 of the incoming water, and means for maintaining the height of the column of water in said stand pipe substantially constant,

- said substantially constant column of water serving to maintain air in said chamber under substantially constant pressure.
7. In a device for obtaining power from waves, the combination with an air and water separating chamber positioned not substantially below the level of the incoming waves, of one or more wave-receiving means discharging into said chamber for 5 delivering the incoming waves to said chamber substantially at the level of the same, a stand pipe connected to said chamber adjacent the bottom thereof and extending above said chamber and also above the level of the 10 incoming water, means for maintaining the height of the column of water in said stand pipe substantially constant, said substantially constant column of water serving to maintain air in said chamber under substantially constant pressure, and means for 15 drawing off the overflow water from said stand pipe.
8. In a device for obtaining power from waves, the combination with an air and 20 water separating chamber positioned substantially at the level of the incoming waves, of one or more wave-receiving means discharging into said chamber for delivering the incoming waves to said chamber substantially at the level of the same, a stand pipe connected to said chamber adjacent the bottom thereof and extending above said chamber and also above the level of the 25 incoming water, means for maintaining the height of the column of water in said stand pipe substantially constant, said substantially constant column of water serving to maintain air in said chamber under substantially constant pressure, means for 30 drawing off the overflow water from said stand pipe, and power-translation means associated with said last-mentioned means for utilizing said overflow water.
9. In a device for obtaining power from 35 waves, the combination with an air and water separating chamber positioned not substantially below the level of the incoming waves, of one or more wave-receiving means discharging into said chamber for delivering the incoming waves to said chamber substantially at the level of the same, a stand pipe connected to said chamber adjacent the bottom thereof and extending above said chamber and also above the level of the incoming water, means for maintaining the height of the column of water in said stand pipe substantially constant, said substantially constant column of water serving to maintain air in said chamber under substantially constant pressure, means for 40 drawing off the overflow water from said stand pipe, and power-translation means associated with said last-mentioned means for utilizing said overflow water.
10. The method of obtaining power from waves, which comprises, in combination, the steps of discharging the waves, consisting of mixed air and water, into a container, 45 said discharge taking place substantially at the level of the incoming waves and the container permitting the air and water to become separated, thereafter causing the air, under compression, in cooperation with the 50 subsequent incoming waves, to act upon the water within the container to raise the same to a substantially constant level above the level of the incoming waves, whereby the air is maintained under a substantially constant pressure, and thereafter drawing off 55 desired portions of the overflow water or of the compressed air for power or other purposes.
- In testimony whereof, I have signed my 60 name to this specification this 27th day of June, 1917.
- WILLIAM SEAMAN SCOTT.
